(57) **CLAIM**

The ornamental design for a toy, as shown and described.

DESCRIPTION

FIG. 1 is a front, right and top perspective view of the first part of the toy, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof; and

FIG. 8 is a bottom plan view thereof.

FIG. 9 is a rear, left and bottom perspective view of the second part of the toy;

FIG. 10 is a front, right and top perspective view thereof;

FIG. 11 is a front view thereof;

FIG. 12 is a rear view thereof;

FIG. 13 is a left side view thereof;

FIG. 14 is a right side view thereof;

FIG. 15 is a top plan view thereof;

FIG. 16 is a bottom plan view thereof.

FIG. 17 is a front, right and top perspective view of the third part of the toy;

FIG. 18 is a rear, left and bottom perspective view thereof;

FIG. 19 is a front view thereof;

FIG. 20 is a rear view thereof;

FIG. 21 is a left side view thereof;

FIG. 22 is a right side view thereof;

FIG. 23 is a top plan view thereof;

FIG. 24 is a bottom plan view thereof.

FIG. 25 is a front, left and top perspective view of the fourth part of the toy;

FIG. 26 is a rear, right and bottom perspective view thereof;

FIG. 27 is a front view thereof;

FIG. 28 is a rear view thereof;

FIG. 29 is a left side view thereof;

FIG. 30 is a right side view thereof;

FIG. 31 is a top plan view thereof;

(Continued)

FIG. 32 is a bottom plan view thereof.
 FIG. 33 is a front, right and top perspective view of the fifth part of the toy;
 FIG. 34 is a rear, left and bottom perspective view thereof;
 FIG. 35 is a front view thereof;
 FIG. 36 is a rear view thereof;
 FIG. 37 is a left side view thereof;
 FIG. 38 is a right side view thereof;
 FIG. 39 is a top plan view thereof;
 FIG. 40 is a bottom plan view thereof;
 FIG. 41 is a combination of third part and fifth part;
 FIG. 42 is a combination of the first part and the third part; and,
 FIG. 43 is a combination of the second part, the third part, and the fourth part.
 The broken lines shown in the drawings illustrate portions of the toy that form no part of the claimed design.
